UNITED STATES PATENT OFFICE.

PHILIP MORINA, OF WASHINGTON, DISTRICT OF COLUMBIA.

CABINET.

Application filed August 8, 1921. Serial No. 490,543.

To all whom it may concern:

Be it known that I, PHILIP MORINA, citizen of the United States, residing at Washington, District of Columbia, have invented certain new and useful Improvements in Cabinets, of which the following is a specification.

The invention relates to improvements in cabinet structure and more particularly to 10 cabinets designed to hold paper in sheets and embodies means for readily exposing the paper from the cabinet for convenient removal therefrom.

The main object of the invention is to 15 provide a paper cabinet having one or more compartments in which a removable drawer is enclosed for holding the paper, said drawer being capable of movement inwardly or outwardly of the compartment for exposing 20 the paper exteriorly of or returning it into the compartment.

An additional object is to provide a cabinet of generally improved design and construction, having novel drawer means and 25 a cover providing a paper rest when opened.

Various other objects and advantages of my invention will become apparent during the continuance of the following description.

30 In the drawings:—

Figure 1 is a perspective view of a paper case or cabinet embodying the invention in its simplest form.

Figure 2 is a vertical cross section of the 35 case, disclosing the movable drawer.

Figure 3 is a top plan view thereof, partly in section, to disclose the drawer top.

Figure 4 is a front elevation of a cabinet embodying the invention in more elaborate 40 form and,

Figure 5 is a vertical transverse sectional view of the cabinet taken on line 5—5 of Figure 4.

In its simplest form the invention embodies a rectangular box or case 1 having 45 its side walls grooved longitudinally, as indicated at 2, and notched at the outer terminals of the grooves as shown at 3 to facilitate grasping pull rods 4 which are slidable in the grooves. The retaining plate 5 straddles each groove adjacent the notch terminal and prevents dislodgment of the pull rod; the plates being suitably fastened to the side wall of the case as shown. Slidably 50 contained within the case is a small

drawer 6 having an inclined bottom 7. This drawer fits snugly within the case for sliding movement therein and normally reposes at the inner end of the case as shown to advantage in Figure 2 of the drawings. The 60 inner terminals of pull rods 4 are connected to the drawer at the side, as shown at 8 and permit the drawer to be slid inwardly or outwardly of the case.

The outward movement of the drawer is 65 limited by stops 9 located in proximity to the open end of the case and adapted to contact with the drawer at the side edges 10 thereof.

By having the bottom of the drawer inclined, it will be observed that the paper is supported in sheets successively projected, one above the other, as shown in Figure 1. The paper sheets can then be separately and conveniently removed from the case as required.

In the elaborate form illustrated in Figures 4 and 5, the invention consists of a cabinet 11 having a drawer compartment for receiving drawer members 12. At the 70 top the cabinet is provided with a dividing partition 13 separating the upper compartment into drawer spaces convenient for holding matter of less size than that insertable in the lower compartments which extend across the entire width of the cabinet as illustrated.

Pull rods 14 which operate the upper drawer members 12 slide in grooves extending along the bottom of the compartment 90 as shown at 15 in Figure 5. Pull rods for the larger drawer members 12 operate in grooves in the side walls of the cabinet and connect up with the drawer members in any suitable manner.

The leg supports 16 of the cabinet embody 95 receptacles 17 for containing pens, pencils or other articles of like character and these receptacles are laterally spaced to provide for the entrance of cover flange 18 therebetween when the said cover 19 is closed. The cover 19 is hinged to the top of the cabinet as shown at 20 and is mounted to swing downwardly over the front of the cabinet for closing the drawer compartment. The 100 cover is provided with upstanding side flanges 21 which engage over the sides of the cabinet when the cover is closed and when the cover is opened it may be thrown back over the top of the cabinet in which 105 110

position it provides a convenient rest for paper removed from the cabinet or waiting to be inserted therein. The flanges of the cover serve to give it the effect of a tray and prevents the papers supported thereby from becoming dislodged or disarranged.

The cabinet may be made of either wood, metal, or other suitable material and of any pleasing design.

From the foregoing it is believed that the advantages and novel features of my invention will be readily understood and therefore further detailed description is deemed unnecessary.

What is claimed is:—

1. A cabinet including a compartment grooved longitudinally of its inner side wall and notched at the outer terminals of the grooves, a drawer slidable within the compartment, pull rods movable in the grooves of the compartment and connected to the drawer for moving the latter inwardly or outwardly of the compartment, the outer end of the pull rod being adapted to locate at the notched terminals of the grooves

when the drawer is at its innermost position within the compartment.

2. A cabinet including a plurality of drawer compartment each of which has its inner side walls grooved longitudinally and notched at the outer terminals of the grooves, a drawer slidable within each compartment, pull rods slidable within the grooves of the compartments and connected to the drawers at their inner end for moving the latter inwardly or outwardly of the compartments, the outer end of the said pull rods being adapted to locate within the notched terminals of the grooves when the drawers are at their innermost position within the compartments, retaining plates straddling each groove adjacent the notched terminals and being fastened to the said walls of the compartment to prevent dislodgment of the pull rod, and a cover hinged to said cabinet and adapted to swing over the front of the cabinet for covering the said compartments.

In testimony whereof I affix my signature,

PHILIP MORINA.
